UNITED STATES PATENT OFFICE

GEORGE O. DRAPER, OF HOPE DALE, MASSACHUSETTS, ASSIGNOR TO THE DRAPER COMPANY, OF SAME PLACE AND PORTLAND, MAINE.

DESIGN FOR A GUIDE-CHUTE FOR LOOMS.

SPECIFICATION forming part of Design No. 30,371, dated March 21, 1899.

Application filed February 20, 1899. Serial No. 706,261. Term of patent 14 years.

To all whom it may concern:

Be it known that I, GEORGE O. DRAPER, a citizen of the United States, residing at Hopedale, in the county of Worcester and Commonwealth of Massachusetts, have invented and produced a new and original Design for a Guide-Chute for Looms, of which the following is a specification.

The drawing shows in perspective a guide-chute for looms, illustrating my design.

The leading feature of my design for a guide-chute for looms consists of a broad body portion having a transverse reentrant portion and a raised lip or flange at one side, with an extended elongated arm at the opposite side, the body portion being reduced in width at its top to form an upward rearwardly-inclined extension adjacent the flange, the body portion and upward extension thereon being both inclined relatively to said arm.

The broad body portion a of the guide-chute

has a transverse reentrant portion a' and a raised lip or flange a^2 at one side, while from the opposite side of the body portion an elongated arm a^3 is extended, the body portion being reduced in width at its top to form an upward extension a^4 thereon adjacent the flange a^2 and rearwardly inclined, said body portion a and the extension a^4 being inclined relatively to the arm. 30

Having fully described my design, what I claim, and desire to secure by Letters Patent, is—

The design for a guide-chute for looms, substantially as herein shown and described. 35

In testimony whereof I have signed my name to this specification in the presence of two subscribing witnesses.

GEORGE O. DRAPER.
